UNITED STATES PATENT OFFICE.

PERCY W. SEAGER, OF LOS ANGELES, CALIFORNIA.

FUEL-FEEDING MEANS FOR INTERNAL-COMBUSTION ENGINES.

1,235,250.

Specification of Letters Patent. Patented July 31, 1917.

Application filed March 19, 1917. Serial No. 155,683.

To all whom it may concern:

Be it known that I, PERCY W. SEAGER, a subject of the King of England, residing in the city of Los Angeles, in the county of 5 Los Angeles and State of California, have invented new and useful Improvements in Fuel-Feeding Means for Internal-Combustion Engines, of which the following is a specification.

10 My invention relates primarily to means for raising the liquid fuel used in automobiles from the main supply tank located below the level of the carbureter into a regulating or distributing tank located above the 15 carbureter from which the fuel will flow by gravity to the carbureter, and it may be used with other engines; the object thereof is to supply a simple and positive apparatus for that purpose.

20 In the drawings forming a part of this application—

Figure 1 is an elevational view of my invention showing it in place on an automobile, shown diagrammatically in dotted lines.

25 Fig. 2 is a vertical section of the intermediate or distributing tank.

Referring to the drawings 5 is an automobile of any make on which the main liquid fuel supply tank 6 is carried at a level below 30 the carbureter 7 of the engine. The distributing tank 8 is preferably placed under the hood of the machine close to the dashboard. Leading from the supply tank 6 to and emptying into the distributing tank 8 is 35 a pipe 9 which when the interior of tank 8 is connected to suction carries the liquid fuel from the tank 6 into tank 8. Extending through the top wall 10 of tank 8 and connected thereto is a valve casing 11 which has 40 a central vertical channel 12 therein which opens at the bottom into tank 8. Above the top of the tank is a port 13 which connects channel 12 with atmosphere and below the top is a port 14 which connects channel 12 45 with the interior of the tank. At a short distance above port 13 channel 12 is contracted and terminates a short distance below the top of the casing. One or more ports or channels 15 extend from near the 50 top of the channel 12 and open through the top of the casing within pipe 16 which pipe connects the casing with the manifold 17 of the engine shown in the dotted lines in Fig. 1. Mounted to move vertically in channel 55 12 is control valve 18 the upper portion of which has a working fit in the contracted

upper portion, and the lower portion has a working fit in the lower portion of channel 12. Between ports 13 and 14 valve 18 is reduced in size so that said ports are connected when tank 8 has its full supply of liquid as hereafter explained and as shown in Fig. 2. Valve 18 has a central longitudinal channel 19 which extends from the top to nearly the bottom thereof. A port 20 60 near the bottom of the channel 19 puts channel 19 in communication at all times with the interior of tank 8. A lever 21 is pivotally mounted by pin 22 in bearing 23 secured to the top 10 and is pivotally connected by pin 24 to the bottom of valve 18. A weight 25 is mounted on the other end of lever 21. Lever 21 has a longitudinal slot 26 therein which permits the lever to slide on pin 22. A guide rod 27 is also pivotally 65 connected to valve 18 by pin 24. Rod 27 has secured thereto a cup 28 which is open at the top and has a transverse partition 29 provided with one or more ports 30. Near the partition, preferably just above is a small 70 port 31 in the side wall of the cup. By the use of a small port in the side wall the level of the liquid in the tank on the outside and inside the cup will lower as the liquid is used, and when the liquid begins to flow into 75 the tank it will flow into the cup faster than it can flow out through the port so that the tank will be nearly full or as shown in Fig. 2, before weight 25 will return valve 18 to break the vacuum. A carbureter supply 80 tank 32 is secured to the bottom of tank 8. The top of tank 8 is removably secured thereon by rods 33 of which there may be any suitable number. One of these rods is hollow and opens into the top of the carbureter supply tank and has a cap on its other end provided with a port 35 which opens to atmosphere. Secured in the bottom of tank 8 and extending to near the bottom of tank 32 is a tube 36 the lower end of which is 85 enlarged to provide a valve casing 37 having a port 38 therein. A cup or check valve 39 has a working fit in casing 37 and is held from dropping out of the casing by cotter pin 40. Connected to the bottom of tank 32 90 is the supply pipe 41 which conveys the liquid to the carbureter. A plug 42 enables the tank to be drained when desired. A plug 43 may be removed for filling tank 8 when 95 starting the device.

100 In the operation of my device we start with tanks 8 and 32 filled as shown in Fig. 110

2. As the liquid is used through the carbureter in the usual manner the level of the liquid in the tank 8 gradually lowers until a sufficient portion of cup 28 is uncovered, which with the liquid contained therein over-balances the weight of weight 25 and connected parts. Valve 18 then descends and cuts off port 13 and at the same time the top of the valve comes below channels 15 thereby throwing the top of tank 8 to the exhaust suction of the pistons of the engine. That portion of valve 18 which is above port 13 when the valve is in the position shown in Fig. 2 is a little narrower 20 than the width of port 13 so that when port 13 is cut off from communication with port 14 suction will operate to finish the downward stroke of the valve 18. The liquid then will be drawn by suction from tank 6 25 into tank 8. This suction also closes valve 39. As the liquid flows into tank 8 it is directed into the top of cup 28 which it quickly fills and then flows over the top. When the liquid fills tank 8 to submerge a large enough portion of cup 28 weight 25 returns valve 18 to the position shown in Fig. 2 and the vacuum in tank 8 is broken and no liquid will pass from tank 6 to 8.

I have shown a small port in cup 28 near the middle of the wall as that construction permits more fuel being used out of the supply tank before the regulating tank will be thrown to suction but said port could be omitted.

35 Having described my invention what I claim is:

1. In combination with an explosion engine in which liquid fuel is used, said engine having a manifold, a carbureter; a main liquid supply tank; a regulating tank above the plane of the carbureter; a pipe connecting said tanks; a valve casing in the top of said regulating tank; said casing having a central vertical channel therein extending from the bottom to nearly the top thereof and ports therein, one connecting to atmosphere, one connecting to the regulating tank and one leading from the side of said channel near the top and terminating in the top; a connection from said casing to the manifold; a valve vertically movable in said channel, said valve having a central longitudinal channel open at the top and having a port near the bottom of the channel and being reduced in size in portions thereof and being adapted to connect the interior of said regulating tank to atmosphere when in its uppermost position and to connect it to suction when in its lowermost position; a carbureter supply tank; a connection between said last tank and said regulating tank; a check valve on said last connection; and a pipe leading from said carbureter supply tank to said carbureter.

65 2. A device of the character described in

combination a main supply tank; a manifold; a regulating tank above the level of the main tank and of the carbureter; a connection between the main and regulating tanks; a carbureter supply tank connected to the regulating tank; a check valve in said last connection; a connection between said supply tank and the carbureter; a connection between the regulating tank and the manifold, said connection comprising a conduit pipe and a valve casing in the top of the tank with ports, one opening into said last pipe, one opening to atmosphere and one opening into the tank, said casing having a central channel open at the bottom, and closed at the top with the upper portion reduced; a valve in said casing, said valve connecting at any one time only two of said ports and closing the other port; and a counter balanced means connected to said valve, said counter balancing means being adapted to have the weight of one side thereof change by the change in volume of the liquid in the regulating tank.

3. The combination with an internal combustion engine having a carbureter and a manifold of a main fuel tank below the engine carbureter; a fuel carbureter supply receptacle located above the carbureter, a connection from said last carbureter supply receptacle to the carbureter; a regulating receptacle; a connection between the regulating and carbureter supply receptacles; a check valve on said last connection; a connection between the regulating receptacle and the main fuel supply tank; a connection from the regulating receptacle to the engine manifold; said last connection comprising in part a valve which in one position connects said regulating receptacle to suction and in another position to atmosphere; and counter balancing means to move said valve from one position to another, said counter-balancing means being adapted to have the weight of one side thereof change by the change in volume of the liquid in the regulating tank.

4. The combination of an internal combustion engine having a carbureter and manifold connected thereto; with a fuel supply tank below the engine carbureter; a carbureter fuel supply receptacle located above the carbureter, a connection from said carbureter supply receptacle to the carbureter; a regulating receptacle; a connection between the regulating and supply receptacles; a check valve on said last connection; a connection between the regulating receptacle and the supply tank; a valve casing in the top of the regulating receptacle having a central channel open at the bottom and reduced in size in the top portion; a pipe connecting the manifold with said valve casing, said casing having a port opening into said pipe and a port opening

into said receptacle, and a port opening to atmosphere; a valve in said casing having a vertical channel extending from the top to near the bottom and having a port near 5 the bottom, said valve being reduced in size at the top and near the bottom and in one position connecting the ports opening to atmosphere and into the receptacle and in the other position connecting the port opening 10 into the pipe with the port opening into the receptacle; a bearing depending from the

cover of said regulating receptacle; a lever pivoted intermediate its ends to said bearing, one end of said lever being pivotally connected to said valve; a weight on the 15 other end of said lever; and a cup having a small port centrally in its side wall connected to said valve.

In witness that I claim the foregoing I have hereunto subscribed my name March 20 1917.

PERCY W. SEAGER.
